UNITED STATES PATENT OFFICE.

ANDREW F. NEWELL, OF WARREN, OHIO.

IMPROVED FRUIT BASKET AND CRATE.

Specification forming part of Letters Patent No. 36,723, dated October 21, 1862.

To all whom it may concern:

Be it known that I, ANDREW F. NEWELL, of Warren, in the county of Trumbull and State of Ohio, have invented new and useful Improvements in Fruit Baskets and Crates; and I do hereby declare that the following is a full and complete description of the construction and operation of the same, reference being had to the accompanying drawings, making part of this specification, in which—

Figure 1 is a perspective view. Fig. 3 is a vertical section. Fig. 2 is a top view with the cover of the crate off, and Fig. 4 is a perspective view of one of the baskets.

The nature of my invention relates to the construction of a skeleton crate, bound at each end with hoop-iron, so arranged that the band forms both hinge and clasp-lock, and to the construction of the fruit-basket, as hereinafter specified, and the manner of packing the same in the crate.

The end pieces, A, of the crate are made of one piece of board each, about eight or twelve inches square. The sides and bottom consist of slats B, about one and a half inch wide and twenty-five inches long. These are nailed to the end pieces, three or four on each side, and three or four on the bottom, according to the height and width. The cover C is composed of one piece of board, and comes flush with the outer edge of the crate on all sides. A band of thin hoop-iron, D, is nailed or screwed to the crate around each end, as seen in Figs. 1 and 2, including the cover. The end of the band E, Fig. 1, extends about one and a half inch beyond the cover, and when the crate is filled, as hereinafter stated, and ready for market, these ends E of the hoop D are slipped inside of the loops F and, are bent outward and upward, as seen in Figs. 1 and 3. The loops F consist of a short piece of band-iron nailed to and around the upper front corners of the crate, as shown in Fig. 1. The fastening thus formed can be clasped and unclasped at pleasure without injury to the crate. The band D at the angle G forms a hinge of sufficient tenacity to allow the crate to be opened and closed many times before the band will break.

The fruit-baskets H, Fig. 4, are of square form, and will hold about one quart each, but the size may be varied. Whatever it may be, the basket must be one-half, one-third, or one-quarter the width and depth of the crate, so as to pack compactly without leaving vacant space.

The sides of the basket consist of one piece of thin wood, (such as is cut by machinery from steamed blocks,) bent at right angles by cutting partly through with a sharp knife, one side being double, as seen at H', and tacked together with small head-tacks, as seen at I. The bottom K consists of six narrow strips of thin wood (same as the sides) woven together, as seen in Fig. 2. The end of each splint is bent at right angles downward, as seen at L in Fig. 3, and each end thus bent down nailed to the sides, as shown in Figs. 3 and 4 at M, which will thus place the bottom K about three-fourths of an inch above the lower edge of the sides.

The body N of the basket is filled with small fruit (as berries) and packed in the crate side by side and one above another, and in consequence of the space below the bottom in each basket there will be no pressure upon the fruit, and none of it will be exposed to view nor subject to being pilfered in transportation, while at the same time the fruit is sufficiently exposed to the fresh air.

The extreme cheapness of these baskets enables the seller to let them go with the fruit sold.

What I claim as my improvement, and desire to secure by Letters Patent, is—

The within-described fruit basket and crate, as a new article of manufacture, consisting of the sides A, cover C, band D with loops F, and the baskets H, all constructed and arranged as and for the purpose substantially as set forth.

ANDREW F. NEWELL.
